UNITED STATES PATENT OFFICE.

CHARLES POLIC AND JOHANN ZIMMERMANN, OF VIENNA, AUSTRIA-HUNGARY, ASSIGNORS TO ACTIEN-GESELLSCHAFT ZUR VERWERTHUNG DER ÖSTER. UND UNGAR. PATENTE TH. LANGER, OF SAME PLACE.

DRAFT-REGULATING APPARATUS FOR FURNACES OF STATIONARY BOILERS.

SPECIFICATION forming part of Letters Patent No. 681,259, dated August 27, 1901.

Application filed June 4, 1900. Serial No. 19,016. (No model.)

To all whom it may concern:

Be it known that we, CHARLES POLIC and JOHANN ZIMMERMANN, subjects of the Emperor of Austria-Hungary, residing at Vienna, 5 in the Province of Lower Austria, in the Empire of Austria-Hungary, have invented certain new and useful Improvements in Draft-Regulating Apparatus for the Furnaces of Stationary Boilers; and we do hereby declare 10 the following to be a full, clear, and exact description of the invention, such as will enable others skilled in the art to which it appertains to make and use the same, reference being had to the accompanying drawings, and 15 to letters and figures of reference marked thereon, which form a part of this specification.

This invention relates to apparatus adapted to regulate automatically the draft in the 20 furnaces of stationary boilers according to the thickness of the layer of fuel on the fire-bars by operating the damper and the fire-door flap or air valve in a suitable manner, so as to fulfil the necessary conditions for 25 smokeless firing.

The mode of operation of the apparatus according to this invention is as follows: When the fire-door is closed, (after stoking,) the damper and the fire-door air-flap are opened. 30 The damper immediately begins to close, at first slowly, but later with greater velocity, and before it reaches its lowest position the air-flap on the fire-door is also automatically closed. These parts are operated by steam-pressure, and the work to be done by the fireman is therefore reduced to a minimum. 35

Such apparatus comprises a steam-cylinder (hereinafter called the "working" cylinder) whose piston is connected to a pulley 40 that operates the damper, to the piston of a brake-cylinder, and to a piston-valve that controls the movement of an air-flap, and a distributor which is actuated by the fire-door and is operated by steam-pressure and which 45 when the fire-door is closed allows steam to flow under the piston of the before-mentioned working cylinder to enable the latter to open the damper and also the air-flap by means of a piston-valve and an auxiliary cylinder

whose piston is operated thereby. When the 50 piston of the working cylinder reaches its highest position, it effects the reversing movement of the distributor, which places the lower end of the said working cylinder into communication with the exhaust, so that the 55 piston can descend, and thereby gradually closes the damper. The downward movement of the piston and the damper is retarded by the piston of a brake-cylinder. Before the piston of the working cylinder reaches 60 its lowest position the steam-supply to the auxiliary cylinder, that holds the air-flap open, is shut off, thereby causing the air-flap to close quickly under the influence of its own weight and of a spring. The minimum opening of the damper can be adjusted according 65 to the rate of working.

Apparatus according to this invention is shown in the accompanying drawings, in which—

Figure 1 is a front elevation, partly in section, of such a draft-regulator with the fire-door. Fig. 2 shows in horizontal section the apparatus that transmits the movement of the piston of the working cylinder to the damper 75 and enables the adjustment of the minimum opening of the damper to be effected.

a is a fire-door which swings on a hinge-bolt *b* and carries a disk *d*, that is provided with a cam portion *c* for raising the piston *e* 80 of the steam-distributer *f* when the fire-door is opened.

g is an air-flap mounted to swing on the fire-door *a* on trunnions, one of which carries a short arm *h*, connected to the piston *k* of 85 an auxiliary cylinder *l* by means of a chain *j* running over a pulley *i*. The auxiliary cylinder *l* contains a spring *m*, continually pressing the piston *k* toward the right, and communicates through a pipe *n* with the steam-inlet and through a pipe *o* with the exhaust. 90

The steam-distributer *f* comprises a cylinder containing a differential piston *p* and the piston *e*. The space above the differential piston *p* communicates through a pipe *q* with 95 the middle portion of the working cylinder *r* and through passages *s* with the space below the piston *e* and the space between the two

parts of the differential piston p . The distributor-cylinder, which is formed with a passage t , communicating with the exhaust-pipe, is in communication through a pipe u with the lower end of the cylinder v and through this cylinder with the steam-inlet w . The distributor-cylinder also communicates through two passages x y at different levels with the pipe z , leading to the lower end of the working cylinder r , which contains a piston 1 , connected to a pulley 4 by means of a rod 2 and a chain 3 , the pulley 4 being coupled to a pulley 5 , around which there passes a chain 6 , leading to the damper. The movement of the piston 1 is transmitted through the rod 2 and double-arm lever 7 to the piston 8 of a brake-cylinder 9 , which is filled with liquid, such as oil or glycerin. The piston 8 is formed with a valve 10 , which opens on the downstroke of the piston and permits the liquid to pass from the space below the said piston to the space thereabove, these two chambers being in communication with each other by a passage 11 , which communicates with the middle portion of the cylinder by a passage 14 . A cock 12 , with a wide aperture 13 , is located in the passage 11 above the passage 14 , and below the passage 14 there is arranged a cock $12'$ with a narrow aperture 15 . Both cocks are formed like screws with fine threads, so as to enable the areas of the apertures to be exactly regulated. The end of a one-arm lever 16 engages with the rod of the piston 8 for the purpose of moving a piston 20 (which is located in the cylinder v and is provided with axial passages 19) against the action of a spring 21 by means of an adjustable cam 18 , mounted on an axle 17 .

The action of the apparatus is the following: When the fire-door a is opened, the projection c on the disk d raises the piston e , which closes the passage y and raises the differential piston p until steam can flow through the passage u below the differential piston p and force the said piston upwardly, so as completely to open the passage u and close the passage x . When the fire-door is open, the damper remains in its lowest position, as steam is prevented from flowing under the piston 1 , since the piston e covers the passage y . Now when the fire-door a is closed after stoking the piston e is lowered by the steam-pressure acting upon it and uncovers the passage y , through which the steam can then flow into the pipe z to the lower end of the working cylinder r , so as to raise the piston 1 and cause the damper to open, the piston 8 of the liquid-brake to descend and the eccentric 18 to force down the piston 20 in the cylinder v , so that the steam can flow from the pipe w through the passage 19 in the piston 20 and the pipe n into the auxiliary cylinder l , so as to move the piston k to the left and open the air-flap g , which remains open as long as the piston k is under steam-pressure. When the piston 1 uncovers the passage q , (i.e., after the damper has been raised,)

the steam flows through the pipe q into the distributor f and again forces down the differential piston p into the position shown, thus closing the passage u and opening the passage x , and thereby enabling the steam under the piston 1 to pass out through the pipe z , the passage, and the pipe t . The piston 1 would then descend quickly, and with it the damper, if this were not prevented by the piston 8 , which is contained in the brake-cylinder 9 and cannot move upwardly faster than is permitted by the liquid flowing through the passage 11 and the narrow aperture 15 . The upward movement of the piston 8 is therefore at first very slow, and the speed increases only after the lower edge of the piston 8 has uncovered the passage 14 , which renders a larger area available for the overflow of the liquid, so that the damper can close slowly at first and afterward more quickly. Before the piston 1 and the damper have reached their lowest positions the piston 20 , pressed upwardly by the spring 21 , closes the passage n and shuts off the steam-pressure in the auxiliary cylinder l , whose piston k is then forced to the right by the spring m , so that the air-flap g can close by its own weight. The damper must never close the flue completely, as otherwise the products of combustion would escape through the fire-door into the stoke-hole. Now it is necessary to alter the minimum opening of the damper during the several periods of working, and to effect this the pulley 5 , to which the chain 6 , leading to the damper, is secured, is loosely mounted on the pin 22 , while the pulley 4 and the disk 23 are keyed to the said pin. The pulley 5 has an annular series of holes 24 and can be coupled to the disk 23 by means of a pin 25 . If, for example, the minimum opening of the damper requires to be increased, (which is necessary in forced working,) the pin 25 is withdrawn from the disk 23 and the pulley 5 when the piston 1 is in its lowest position, and the pulley is turned by means of its handle 26 , so that the damper is raised, whereupon the disk 23 and the pulley 5 are again coupled together by means of the pin 25 . The time required for the descent of the damper can be exactly regulated by means of the regulating-screws that constrict the area of the overflow-passages 11 and 13 of the brake-cylinder 9 . The time during which the steam-supply to the pipe n is interrupted, whereby the closing of the air-flap g is effected, can be altered at will by suitably adjusting the eccentric 18 on the shaft 17 . The eccentric 18 can even be so adjusted that the air-flap does not open at all.

We claim—

1. In a draft-regulator, a steam-distributer set in operation by the furnace-door, a steam-cylinder steam-connected to the distributer, a piston in said cylinder arranged to operate a damper, means for braking the steam-piston after steam-supply thereto has been cut

off, said distributor arranged to cut off the steam-supply to the steam-cylinder when its piston has nearly completed its travel, substantially as set forth.

5. 2. In a draft-regulator, a steam-distributer set in operation by the furnace-door, a steam-cylinder steam-connected to said distributer at one end, a second steam connection from the steam-cylinder to the distributer arranged to be opened when the steam-piston has accomplished part of its travel, a brake-cylinder, its piston, a pivoted lever connected at one end to the steam-piston and at the other to the brake-piston, and a damper operated by the steam-piston, substantially as set forth.

3. In a draft-regulator, a steam-distributer and differential piston-valve operatively located therein to cut off the steam-supply, means operated from the furnace to displace 20 the differential valve, a steam-cylinder, a steam connection between one end thereof and the steam-distributer at a point below the differential valve, and a steam connection between said cylinder intermediate its 25 ends and the steam-distributer at a point above the differential valve and a damper operated by the steam-piston, substantially as set forth.

4. In a draft-regulator, a steam-distributer comprising a suitable casing, a differential piston-valve therein comprising two connected pistons of different sizes, one of them controlling a steam-inlet port, a piston in said casing arranged to displace the differential 35 valve, a steam by-pass connecting both ends of the casing and a branch passage connecting the by-pass with the interior of the casing intermediate the pistons of the differential valve and arranged to be closed by one 40 of them; in combination with a steam-cylinder and its piston steam-supplied through the distributer, and a steam connection from said steam-cylinder to the differential valve, substantially as set forth.

5. 5. In a draft-regulator, a steam-distributer comprising a suitable casing, a differential piston-valve therein comprising two connected pistons of different sizes, one of them controlling a steam-inlet port, a piston arranged to start the opening of the differential 55 valve, a steam by-pass connecting the top and bottom of said casing, a steam-chamber, passages connecting it with the interior of the casing above and below one of the pistons of the differential valve, an exhaust, said exhaust and one of the passages between the steam-chamber and interior of the casing capable of being closed by the differential valve, and steam inlets and outlets, substantially as set forth.

6. In a draft-regulator, a steam-distributer, a steam-cylinder supplied therefrom, and provided with a steam-outlet intermediate its ends, a piston and rod, a damper operatively connected to one end of said rod and a brake-cylinder, its piston and rod, a pivoted lever connecting the rods of the brake and steam

pistons, a steam-cut-off valve, a tappet to operate said valve actuated by the brake piston-rod, substantially as set forth.

7. In a draft-regulator, a steam-distributer, a steam-piston contained within a steam-circuit from and to the distributer, a piston and rod in the cylinder operatively connected to a damper, a brake-cylinder adapted to contain a liquid, a piston provided with a valve normally closed when braking, its piston-rod, the steam and brake piston-rods operatively connected, a by-pass connecting the ends of the brake-cylinder, said by-pass having constricted passages near its ends one smaller than the other, and a passage intermediate the constricted portions to communicate with the interior of the brake-cylinder arranged to be closed by the brake-piston when near 85 the limit of its braking stroke, substantially as set forth.

8. In a draft-regulator, a steam-distributer, a steam-piston contained within a steam-circuit from and to the distributer, a piston and its rod in the cylinder operatively connected to a damper, a brake-cylinder adapted to contain a liquid, a piston provided with a valve normally closed when braking, its piston-rod, a pivoted lever connecting the ends of the steam and brake piston-rods, a by-pass connecting the ends of the brake-cylinder, means near the ends of the by-pass for constricting and regulating the degree of constricture in said by-pass, the free passage being smaller 100 near the end of the braking stroke, a port intermediate the constricted portions of the by-pass communicating with the interior of the cylinder arranged to be closed by the braking-piston when near the limit of its braking 105 stroke, substantially as set forth.

9. In a draft-regulator, the combination with a furnace-door flap, an actuating device comprising a steam-cylinder, a spring-retracted piston therein and its piston-rod operatively connected to actuate the furnace-door flap; of a spring-retained steam-cut-off valve, a steam-distributer connected thereto and steam-actuated devices supplied from the distributer for actuating the steam-cut-off valve, substantially as set forth.

10. In a draft-regulator, the combination with a furnace-door, a flap mounted on trunnions thereon, a steam-cylinder, a spring-retracted piston and rod therein, said rod operatively connected to the flap; of a spring-retained steam-cut-off valve, a steam-distributer, a steam-actuated piston arranged to actuate a damper, a braking-piston connected to the steam-actuated piston, a cam, its actuating-lever operated by the braking-piston to operate the steam-cut-off valve, substantially as set forth.

11. In a draft-regulator, the combination with a steam-cylinder, its piston and rod and means for supplying steam to said cylinder, a pulley, a flexible connection between the pulley and rod, a pulley provided with a handle connected to a damper, a spindle fixed

thereto, the first-mentioned pulley loose on said spindle and means for adjusting and connecting the loose pulley to the one operating the damper, thereby adjusting the degree of closure of the latter, substantially as set forth.

12. In a draft-regulator, the combination with a furnace-door and a rod, a cam carried thereby; of a steam-distributer comprising a suitable casing, a differential valve therein consisting of two connected pistons of different sizes, a piston and its rod below the differential valve arranged to be cammed by the cam on the furnace-door to start the differential valve, a steam by-pass connecting the end of the distributer, a port intermediate the ends of the by-pass to connect it intermediate the pistons of the valve, a steam-

chamber and two ports connecting it with the valve-chamber, an exhaust-port intermediate the pistons of said valve, one of the pistons of the valve arranged to control the exhaust-port, one of the ports to the steam-chamber and the one to the by-pass, and a steam piston and cylinder to actuate a damper operatively included in a steam-circuit from and to the distributer, substantially as set forth. 20 25

In testimony that we claim the foregoing as our invention we have signed our names in presence of two subscribing witnesses.

CHARLES POLIC.
JOHANN ZIMMERMANN.
